UNITED STATES PATENT OFFICE.

WALTER A. GARRATT, OF COVINGTON, KENTUCKY.

SOUNDING DEVICE.

Application filed November 26, 1919. Serial No. 340,833.

To all whom it may concern:

Be it known that I, WALTER A. GARRATT, a citizen of the United States, and a resident of Covington, in the county of Kenton and State of Kentucky, have invented certain new and useful Improvements in Sounding Devices, of which the following is a full, clear, and exact description, reference being had to the accompanying drawings, 10 forming a part of this specification.

My invention relates to sounding devices for automobiles, motor boats, or other mechanisms, being more particularly directed to sounding devices for mechanisms employing 15 internal combustion engines.

It is my object to provide a sounder or horn, which gives a novel tone, same to be preferably regulated by a simple adjustment to change its pitch. Although my 20 horn might be adapted to use with air or steam pressure, it is one of the objects of my invention to provide a sounding device which will operate by the suction or vacuum, resulting from the suck of the pistons in 25 internal combustion engines.

So far as I am aware it has not been developed in the past that a sounder may be successfully employed in connection with the suction of, for example, a gasoline engine intake manifold, for the reason among 30 other things, that the principles necessary in connection with the development of sound at will from a suction of the nature of the intake manifold suction have not been 35 worked out or understood.

In connection with the mode of development of the novel tone above referred to, it is my object to employ a part corresponding in appearance to the diaphragm of an ordinary sounder, as a reed or generating mechanism for combined air and diaphragm vibrations, thereby producing sound in a novel manner. The sound features of my devices to be described, are adaptable from 45 this point of view to a wide range of instrumentalities, such as organs, steam pianos, and wind instruments generally.

My various objects and advantages I accomplish by that certain construction and 50 arrangement of parts to be hereinafter more specifically pointed out and claimed.

In the drawings,

Figure 1 is a perspective view of an internal combustion engine having my device attached thereto.

Figure 2 is a central longitudinal section of my device.

Figure 3 is a plan view of the membrane or reed, in the nature of a diaphragm, that is used by me.

Figure 4 is an enlarged longitudinal section through the adjustable sound controlling mechanism of the sounding device shown in Figure 2.

It should be understood that while one specific device has been selected by me as illustrating a mechanism by means of which the advantages of my invention may be gained, that I do not wish to limit myself to this one form, because of my failure to show 65 and describe all or even a few of the variations therefrom which occur to me.

As shown in Figure 1, the device selected for illustration is employed with an internal combustion engine 1, having an intake 70 manifold 2, to the engine cylinders. Motors of this character receive the fuel which is expanded or burnt internally, by means of suction set up by the pistons in the cylinder, as controlled by the valves of the engine, 75 and this suction being coupled up to the carburetor 3 of the engine.

The sounder itself is made up of a trumpet or funnel shaped horn 4, suitably mounted in an annular front plate 4^a, the 80 horn and annular plate comprising the sound projecting portion of the device, the particular shape or dimension thereof, being unessential.

It further comprises a back plate 5, which 85 has a centrally mounted, interiorly threaded boss 6, and said back plate and front plate are secured together by means of bolts 7.

Intermediate the two plates, is a thin resilient disk 8, preferably of sheet metal, 90 which is pierced with holes 9 about its periphery to receive the bolts 7, and is clamped between the front and back plates, protected by means of suitable gaskets 10, 100 on each side thereof.

Extending rearwardly from the back plate is some suitable and convenient form of protective shell, such as the shell 11, which is also held in place by the bolts 7.

The disk 8 is provided at its center with 105 a fairly large hole 12, around which is a flange or ring 13, which, preferentially, extends beyond the plane surface of the disk. This flange acts as the movable part of a valve seat in connection with the production 110

of sound, and also serves to some extent as a hammer in connection with the balance of the valve, and the disk.

- 6 The valve has a threaded stem 14, which is held in the boss 6, and secured adjustably therein by a nut 15. The stem carries on its end a fairly heavy metal plate 16, a small washer 17, and a thin copper washer 18, which co-operates directly with the 10 flange on the disk. I have found that this washer or plate 18 may be omitted without entirely eliminating the advantageous features of sound reproduction, but for ideal operating conditions it should be present. 15 The plate or valve head 16, the small spacing washer 17 and the thin copper plate 18 are held on the end of the stem in a permanent manner by means of a screw 19 threaded into the stem 14.
- 20 By adjusting the stem in the boss, as above described, the tension of the contact of the copper plate with the central flange on the main disk can be regulated and hence the sound quality of the instrument.

- 25 The intake manifold of the internal combustion engine will be tapped into by a pipe 20, in which is any suitable valve 21 which may be controlled from the driver's seat. The pipe will then extend through the shell 30 and by suitable nipple 22, be connected to the suction pipe 23, that pierces the rear of the back plate of the sounder.

This pipe 23 must be of small diameter, in comparison to the space which will be 35 opened through the sounding disk or valve plate, or the device cannot operate practically from manifold intake suction.

The operation of the sounding device is effectuated by opening the valve 21, and 40 permitting suction from the manifold to exhaust the air in the space behind the disk. This suction will lift the disk central flange away from its seat, whereupon the suction will be reduced to such an extent, due to the 45 comparative size of the suction inlet and the valve opening, that the central flange or valve member 13 will fly back with great force against its seat (the copper washer).

The number and force of the vibrations 50 will be controlled by the tension exerted against the disk by the adjusted position of the valve stem or post 14, and, of course, by the natural resiliency of the disk itself. The nature of the vibration will also be materially affected by the resiliency or pliability of the copper washer, 18.

The leaving of too large an outlet 23 in the back space or vacuum chamber of the sounder to the engine intake, would require 60 a very large opening of the valve, in order to reduce the suction to a sufficient degree to permit of the necessary rapid oscillation of said valve. The diameter of the effective opening in the valve must be, necessarily, 65 larger than the discharge to the manifold

in order to insure the prompt release of the suction in the said chamber and to prevent the flange being lifted and held from its seat.

Should the openings both be of large size, 70 even if the valve opening is larger than the outlet, the result would be that the suction in the manifold would be so reduced as to injuriously affect the intake of explosive mixture into the engine cylinders. 75

By properly proportioning the parts therefore, it is readily possible to utilize manifold intake suction to operate a sounding device, particularly where this sounding device is in the nature of a valve, which 80 rises and falls from its seat, in extremely rapid vibrations.

The degree to which the disk or membrane itself adds to the sound due to its own vibrations, has been difficult for me to determine. I am confident that the result of the hammering of the valve ring or flange at the center of the disk on the valve head, or copper washer, does produce some sound in the disk, independent of the sound resulting from the rapid interruptions in the air current. My reason for this is that the sound produced by my sounding mechanism is different from the sound of any valved or reed instrument with which I am 90 familiar. 95

The adjustments of the stem will give a range of sound varying from a low sweet sound, to a high shrill whistle, and throughout the scale, there are not any evident pulsations due to the variability of the suction in the manifold. The restricted size of the outlet from the vacuum chamber, is the reason for this, and this is a further feature in connection with the use of manifold intake suction for operating a sounder. 100 105

It should be noted that the sounding device described could be operated by pressure as distinguished from suction, either directly or by an inversion of the valve. 110 115

Having thus described my invention, what I claim as new and desire to secure by Letters Patent is:—

1. The combination with the intake manifold of an internal combustion engine, comprising a chamber, a resiliently mounted valve in the chamber adapted to open and close for production of sound, and connection from the said manifold to the said sounding device for operating the valve, 120 said connection having a smaller passage therethrough than in the exposed area of the valve when open. 115

2. A sounding device comprising a chamber, a peripherally held disk closing the 125 chamber, said disk having an opening therein intermediate its edges and means against which the sides of said opening abut when the said disk is at rest, and forming a seat therefor and an inlet to said chamber for 130

supplying suction thereto for the purpose described, said inlet being of small diameter in comparison with the disk opening.

3. A sounding device comprising essentially a chamber at least one wall of which embodies a resilient disk, said disk having an opening therein intermediate its edges, a valve formed about said opening and a seat for said valve, and means for forming a 10 partial vacuum in said chamber to unseat said valve.

4. A sounding device comprising essentially an air chamber, a resilient disk closing said air chamber, said disk having a central 15 aperture, a valve formed around said aperture, a valve seat comprising a thin disk positioned to normally contact with said valve, and means for varying the normal pressure of air in the air chamber to cause 20 vibration of the valve on the seat, said means

embodying an inlet into said air chamber of different size from the outlet.

5. A sounding device comprising a back plate, a disk held peripherally in position forming a chamber with said back plate, a 25 stem adjustably held in the back plate, said disk having an aperture for the passage of said stem, a ring set around said aperture to serve as a valve member, and means on the stem to normally abut the ring, for the 30 purpose described.

6. A sounding device comprising essentially a valve having a resilient disk, said disk having an opening therein intermediate its edges, a valve formed about said opening 35 and a seat for said valve, and means for causing passage of air through the space between the valve and its seat, said seat comprising a resilient copper disk.

WALTER A. GARRATT.
